CLAIM

The ornamental design for a ceiling light, as shown and described.

DESCRIPTION

1. Ceiling light

The design is a ceiling light consisting of a first cylindrical body extending along a vertical axis and a second cylindrical body extending along a horizontal axis and supported by the first body; each cylindrical wall has an opaque portion and a translucent portion; the opaque portion of the second body is joined to the opaque portion of the first body; each body houses a LED light source; The break lines in the drawings indicate that the appearance of any portion of the ceiling light between the break lines forms no part of the claimed design. Fig. 1.1 is a perspective view of the design; Fig. 1.2 is a front view thereof; Fig. 1.3 is a rear view thereof; Fig. 1.4 is a left view thereof; Fig. 1.5 is a right thereof; Fig. 1.6 is a top view thereof; Fig. 1.7 is a bottom view thereof.
